CORRECTION CIRCUITS

Edward W. Herold, Verona, N. J., assignor to Radio Corporation of America, a corporation of Delaware

Application August 24, 1939, Serial No. 291,630

10 Claims. (Cl. 250—20)

My present invention relates to correction circuits generally, and more particularly to signal transmission tube circuits utilizing specially designed networks for correcting various undesired conditions.

One of the main objects of my invention is to provide a novel means whereby undesirable effects caused by the finite time of transit of the electrons in certain types of vacuum tube are cancelled.

Another important object of this invention is to provide a means whereby a tube whose control grid lies in a current-limited region may be used in an amplifier or converter whose input is tunable over a wide frequency range without the limitation of amplification by electronic transit-time effects.

Another object of this invention is to provide a tube amplifier or converter whose performance is made substantially independent of transit time effects by the connection of an external impedance, and which is capable of operating up to frequencies of 100 megacycles (mc.) and higher.

Yet another object of my invention is to provide a frequency converter arrangement for superheterodyne receivers in which the undesired coupling between oscillator and signal circuits, and which is largely due to electronic effects within a tube, are cancelled over a wider frequency range than has heretofore been possible.

Still other objects of my invention are to improve generally the stability and efficiency of high frequency amplifiers and converters, and more especially to attain these ends in a simple and economical manner.

The novel features which I believe to be characteristic of my invention are set forth in particularity in the appended claims; the invention itself, however, as to both its organization and method of operation will best be understood by reference to the following description taken in connection with the drawing in which I have indicated diagrammatically several circuit organizations whereby my invention may be carried into effect.

In the drawing:

Fig. 1 shows one form of the present invention applied to a tunable high frequency amplifier.

Fig. 2 shows curves of the electronic input conductance of a particular tube when used alone, and when combined with two forms of the present invention, and is included to show the behavior of the invention in a specific example, and

Fig. 3 shows the present invention applied to

the cancellation of electronic coupling effects in a converter tube.

Among the chief limitations of amplifier and converter tubes to be operated at high frequencies are electronic effects which are caused by the finite time of transit of electrons in their passage through the tube. With the conventional space-charge control tube, for example, it is found that the conductive component of the input impedance increases with frequency to a point where it may be the limiting factor in the amplification of the tube. One method of improving such tubes for use at high frequencies has been to decrease the inter-electrode spacings so as to reduce the electronic transit time. Another improvement may be effected by operation at higher voltage. Both these methods, however, have serious structural limitations and cannot be said to have extended the practical upper frequency limit of operation of tubes to more than three or four times that formerly attained. Furthermore, below the limiting frequency at which amplification is no longer possible, the operation of space-charge control tubes is accompanied by considerable input loading so that the latter becomes an extremely important factor in circuit design.

An entirely different solution to the problem is presented by my invention which makes use of tubes in which space-charge control is not the predominant factor whereby the anode current of a tube is regulated. In the type of tube known as a space-charge grid tube, for example, the electrons approaching the control electrode do so at high velocity and are decelerated in approaching it. The control electrode in such a tube does not necessarily operate by varying the space-charge conditions adjacent to it, but may be made to operate merely as a gate which allows more or fewer electrons to pass depending on its potential. The effect of electronic transit time on the input impedance of the control electrode may be quite different in such tubes over the effect in the more conventional space-charge controlled tubes wherein electrons leave a thermionic cathode at very low velocities and are eventually accelerated towards the adjacent control grid. In fact, it has been found that the input conductance of a suitably-biased control grid in a space-charge grid tube is negative rather than positive as with the conventional tube. While the positive input conductance of the conventional tube reduces the amplification by its loading of the input circuit, the negative input conductance of a

properly operated space-charge grid tube actually increases the amplification.

It has been found that a negatively-biased electrode exhibits negative conductance when it is so operated as to be in a current-limited region. With the conventional tube, for example, if the cathode temperature is reduced to the point at which the entire emission current leaves it, the control grid conductance is found to be negative.

Under such conditions, however, the control grid potential would affect the current only slightly, and the tube would be virtually useless as an amplifier. The control electrode of a properly constructed and operated space-charge grid tube, however, may be made to have a very great control action, and yet have a negative conductance. It has also been found that the negative input conductance increases approximately in magnitude with the square of the frequency as: $g_{in} = -k\omega^2$ where g_{in} is the input conductance, ω is the angular frequency, and k is a constant which depends on the tube configuration and operating voltages. At low frequencies, therefore, as with most other transit-time effects, the input conductance is frequently so small that it may be neglected. At high frequencies, however, the conductance becomes important and may be sufficiently negative to excite oscillations in the input circuit.

An amplifier or converter tube whose input conductance varies markedly with frequency is not always desirable, and is particularly objectionable in amplifiers whose input circuits must be tuned over a wide range. When the input conductance is positive, it is objectionable because the amplification is reduced by varying amounts depending on the frequency, while, when it is negative, the amplification is increased by varying amounts and instability may result due to self-oscillation at some adjustments.

It is the purpose of my invention to reduce the variable negative conductance substantially to zero at all frequencies by the utilization of an equal and opposite positive conductance which varies in the same way.

Considering a circuit consisting of a resistance R and capacitance C in series, it is found that such a circuit behaves similarly to a parallel circuit of a conductance G_{eff} and capacitance C_{eff} where:

$$G_{eff} = \frac{\omega^2 C^2 R}{1 + \omega^2 C^2 R^2}$$

and

$$C_{eff} = \frac{C}{1 + \omega^2 C^2 R^2}$$

and ω is the angular frequency. For frequencies below a certain point

$$(e.g. \omega < \frac{0.3}{CR})$$

the term $\omega^2 C^2 R^2$ in the denominator may be neglected in comparison with unity and such a circuit behaves substantially as a positive conductance whose value varies as the square of the frequency, in parallel with a constant capacitance. If such a series C and R circuit be connected across the input of a properly constructed and operated tube with a control grid in a current-limited region so that it has an input conductance $g_{in} = -k\omega^2$ the total conductance will be

$$G_{total} = \frac{\omega^2 C^2 R}{1 + \omega^2 C^2 R^2} - k\omega^2 \approx \omega^2 (C^2 R - k) \left[\omega \leq \frac{0.3}{CR} \right]$$

It is evident that, if $k = C^2 R$, the total con-

ductance will be substantially zero, independently of frequency up to some limiting point

$$(e.g. \omega \leq \frac{0.3}{CR})$$

By making C larger and R smaller, the upper frequency limit may be extended as much as desired. It is, of course, undesirable to add an excessive amount of capacitance, and it is, therefore, impracticable to use such a C and R circuit for correction up to too high a frequency for a given tube.

Considering a circuit consisting of inductance L , resistance R and capacitance C in series and with $L = \frac{1}{2}CR^2$ I have found that such a combination behaves similarly to a parallel circuit of conductance G_{eff} and capacitance C_{eff} where

$$G_{eff} = \frac{\omega^2 C^2 R}{1 + \frac{1}{4}\omega^4 C^4 R^4}; C_{eff} = \frac{1 - \frac{1}{2}\omega^2 C^2 R^2}{1 + \frac{1}{4}\omega^4 C^4 R^4}$$

This series circuit behaves substantially as a positive conductance increasing as the square of the frequency up to a much higher frequency than the simple C and R series circuit. For a 10% departure from the square-law relation, the L , C , R circuit is satisfactory up to

$$\omega = \frac{0.8}{CR}$$

where the simple C and R circuit is satisfactory only to

$$\omega = \frac{0.3}{CR}$$

Thus, the L , C and R circuit may be connected to a tube with a control electrode in a current-limited region to obtain a zero input conductance amplifier or converter up to a much higher frequency for the same added capacitance, or up to the same frequency for a much reduced capacitance as compared with the C - R circuit. It is, of course, necessary that the conditions

$$L = \frac{1}{2}CR^2, \text{ and } C^2 R = k$$

be substantially realized in order to achieve this favorable result.

Fig. 1 shows a form of the invention as applied to a high frequency amplifier tunable over a wide range. An amplifier tube 1 comprising a cathode 2, a control electrode 3, an anode 4 and auxiliary electrodes 5 and 6 is shown connected to a signal input circuit 7, and an output circuit 8. A positive potential is applied to the auxiliary electrodes 5 and 6 which serve as a space-charge grid and screen grid respectively. By-pass condensers 9 and 10 are included to insure that alternating potentials are not present on electrodes 5 and 6. The control electrode 3 is operated in a substantially current-limited region between electrodes 5 and 6, and has an input conductance whose value is negative and increases as the square of the frequency following the relation: $g_{in} = -k\omega^2$. A series circuit of capacitance 11, resistance 12 and inductance 13 is connected between the control electrode and ground, and is so chosen that $L = \frac{1}{2}CR^2$ and $C^2 R = k$.

Fig. 2 shows the manner in which the total conductance caused by the tube varies with frequency with and without the connection of the compensating circuits. The curve labelled "No correction" shows the measured input conductance of a particular amplifier tube as plotted against frequency. Examination of the data

shows that this tube approximately obeys the relation $g_{in} = -0.5 \times 10^{-20} \omega^2$. Making

$$C^2 R = 0.5 \times 10^{-20}$$

5 and choosing a small value for C such as 4 mmf., the values $C=4$ mmf., $R=311$ ohms are obtained. The curve labelled "C-R correction" shows the input impedance with this C and R series circuit across the tube. The input conductance will be 10 seen to be approximately zero up to nearly 30 megacycles. By adding a series inductance

$$L = \frac{1}{2} CR^2 = 0.2 \times 10^{-6}$$

15 henries, the curve labelled "C-R-L correction" is obtained. This curve gives an approximately zero input conductance up to nearly 100 megacycles. It should be noted that inasmuch as the value of inductance required in series with the C-R combination is quite small, it may frequently 20 be obtained through the use of lead wires to C and R of the proper length and geometrical configuration.

Another undesirable electronic effect which is 25 found in some types of converter tube at high frequencies may also be corrected according to my invention. Fig. 3 shows the invention as applied to the reduction of "space-charge coupling" in a pentagrid converter. The converter tube 11 has the grids 12, 13, 14, 15, 16 interposed in the 30 order named between cathode 17 and anode 18. Signal voltages are applied to the tunable input circuit 19, the high potential end of which is connected to the signal grid 15. Bias for the latter may be obtained from either the usual self-bias 35 network in the cathode lead, or from an A. V. C. network. The oscillator section of the converter comprises cathode 17, oscillator grid 12, oscillator anode-grid 13 and the circuits associated therewith. The tunable circuit 13' connected between 40 oscillator grid 12 and cathode 17 determines the frequency of the local oscillations. The intermediate frequency output circuit 20 is connected in 45 circuit with plate 18. The intermediate frequency oscillations are utilized in any manner well known to those skilled in the art.

As has been explained in my U. S. Patent 2,141,750 granted December 27, 1938, the operation of a pentagrid converter is accompanied by an electronic "space-charge" coupling between 50 oscillator and signal circuits which may be neutralized or cancelled by the connection of a suitable network. In the aforementioned patent it was shown that a series connection of a condenser and resistance was effective to secure the 55 space charge coupling neutralization over a fairly wide range of frequencies up to an upper limit frequency of about 40 mc. It is not believed necessary to repeat here the theoretical aspects of the neutralization action, as the aforesaid patent fully explains the design and effects of the C-R neutralization network.

In the present arrangement there is employed 60 a series path comprising capacity 21, resistor 22 and inductance 23 as the neutralization network. 65 Cancellation of the space charge coupling effect between the oscillator and signal grids is secured thereby over a wider frequency range than with the series C-R circuit of the aforesaid patent. For best results the same values of C and R (21 and 22) are chosen as in the circuit of my said 70 patent. The value of inductance 23 is made approximately equal to

$$\frac{CR^2}{2}$$

The space charge coupling is thereby effectively cancelled to a frequency approximately twice as high as with inductance 23 omitted. Since the value of L₂₃ is usually quite small (just as in the correction of input conductance as hereinbefore explained), it may frequently be obtained through the use of lead wires to C and R of the proper length and geometrical configuration. Although the circuit shown in Fig. 3 is for a pentagrid converter it is obvious that the method 10 applies to any mixer or converter tube in which inner-grid oscillator injection is used.

While I have indicated and described several systems for carrying my invention into effect, it will be apparent to one skilled in the art that 15 my invention is by no means limited to the particular organizations shown and described, but that many modifications may be made without departing from the scope of my invention, as set forth in the appended claims.

What I claim is:

1. In a high frequency amplifier, an electron discharge tube of the type whose control grid is surrounded by a positive potential field and is in a current-limited region and has a negative input conductance, a signal input circuit coupled to the control grid, and means electrically associated with the input circuit for cancelling the effect of the negative input conductance of said tube. 30

2. In a high frequency amplifier, an electron discharge tube of the type whose control grid is surrounded by a positive potential field and is in a current-limited region and has a negative input conductance, a signal input circuit coupled 35 to the control grid, and means comprising capacitance and resistance electrically associated with the input circuit for cancelling the effect of the negative input conductance of said tube. 40

3. In a high frequency amplifier, an electron discharge tube of the type whose control grid is surrounded by a positive potential field and is in a current-limited region and has a negative input conductance, a signal input circuit coupled to the control grid, and means electrically associated with the input circuit for cancelling the effect of the negative input conductance of said tube, said means consisting of a series path of 45 capacitance and resistance connected across said input circuit. 50

4. In a high frequency amplifier, an electron discharge tube of the type whose control grid is surrounded by a positive potential field and is in a current-limited region and has a negative input conductance, a signal input circuit coupled 55 to the control grid, and means electrically associated with the input circuit for cancelling the effect of the negative input conductance of said tube, said means consisting of capacitance, resistance and inductance arranged in series across 60 the input circuit. 65

5. In a high frequency amplifier, an electron discharge tube of the type whose control grid is surrounded by a positive potential field and is in a current-limited region and has a negative input conductance, a signal input circuit coupled to the control grid, and means electrically associated with the input circuit for cancelling the effect of the negative input conductance of said tube, said means consisting of resistance, capacitance and inductance chosen to cancel said negative conductance over a range up to 100 megacycles. 70

6. In an amplifier network of the type utilizing a tube whose control grid is surrounded by a 75

positive potential field and is in a current-limited region and whose input conductance is negative, and a circuit connected to said control grid for cancelling the effect of said negative conductance over a wide range of frequencies.

7. In an amplifier network of the type utilizing a tube whose control grid is surrounded by a positive potential field and is in a current-limited region and whose input conductance is negative, 10 and a circuit, comprising at least capacitance and resistance arranged in series, connected to said control grid for cancelling the effect of said negative conductance over a wide range of frequencies.

15 8. A frequency mixing network comprising a multi-electrode tube, a signal frequency circuit connected to one of the electrodes, a local oscillator circuit connected to another of the electrodes, said last two electrodes having undesired 20 interaction, and means for cancelling said interaction comprising capacitance, resistance and inductance connected in series between said two electrodes, and said inductance being approximately equal to one half the product of the capacitance and the square of the resistance.

25 9. In a high frequency amplifier, an electron discharge tube of the type whose control grid is surrounded by a positive potential field and is in

a current-limited region and has a negative input conductance, a signal input circuit coupled to the control grid, and means electrically associated with the input circuit for cancelling the effect of the negative input conductance of said 5 tube, said means consisting of capacitance, resistance and inductance arranged in series across the input circuit, and said inductance being approximately equal to one-half the product of the capacitance and the square of the resistance. 10

10. In a high frequency signal-translating circuit which includes an electron discharge device having at least two electrodes between which undesired phenomena are present, said undesired phenomena exhibiting the effect of a substantially constant negative capacitance and a negative conductance whose value increases with frequency, a correcting circuit comprising a positive capacitance, a positive resistance and a positive inductance connected in series between the two 15 aforesaid electrodes and proportioned so as to substantially cancel at least the said negative conductance effects over a wide frequency range and said inductance having a magnitude equal to one half the product of the capacitance and 20 the square of the resistance.

EDWARD W. HEROLD.
